[57] **ABSTRACT**

A method and apparatus for formulating an ink capable of reproducing a desired color having an unknown ink formulation. The apparatus includes a viewing area adapted to receive a color sample having a known ink formulation as well as a sample of the color having an unknown ink formulation. A number of filters are mounted above the viewing area such that any number or combination of the filters may be selectively positioned to overlie the known color sample until the unknown color is approximately duplicated by the known color sample and superimposed filters. The color of each filter is reproducible by a known ink formulation, and thus an ink capable of reproducing the unknown color may be prepared by mixing an appropriate amount of the inks indicated by the selected filters with the ink of the known sample.

on the lower half of the viewing area 30 in juxtaposition with the unknown sample. Next the technician, while viewing the area 30 through the eyepiece 29, selectively positions any number or combination of the filters over the lower half of the viewing area and thus the known sample, until the color of the unknown sample is approximately duplicated. Since the color of the filters carried by the arms are each reproducible by a known ink, the inks indicated by the known color sample and selected filters may be mixed to produce an ink capable of reproducing the unknown color.

As will be apparent from FIG. 2, the incident light directed onto the viewing area 30 from the light 31 and through the open front of the apparatus does not pass through the filters, and the light reflected from the viewing area passes upwardly through the selected filters to the observer.

By way of specific example, the procedure for formulating a lithographic ink capable of reproducing a desired unknown color and utilizing the present invention is described below. As is well known, lithographic inks typically comprise approximately 40-70 percent coloring pigments, with the remainder comprising the "vehicle" (i.e., varnish, dryers, etc. suitably formulated for lithographic printing). Initially, a number of base color samples reproducible by known ink formulations were selected. The exact number and color of these samples could vary, and are generally determined by experience. The samples may but do not necessarily represent the "primary" colors. For the present example, six base color samples were selected as follows:

Base Color Sample Inks	% Pigment	% Vehicle	
1. Benzine Yellow	55.25	44.75	
2. Warm Red	67.40	32.60	
3. Magenta	41.85	58.15	
4. Rubine Red	63.65	36.35	
5. Reflex Blue	59.85	40.15	
6. Purple	58.85	41.15	

Next, six toner inks were selected for the six groups of filters as follows:

Toner Inks	% Pigment	% Vehicle	
1. Red	50.00	50.00	
2. Green	50.00	50.00	
3. Blue	50.00	50.00	
4. Yellow	50.00	50.00	
5. Magenta	50.00	50.00	
6. Cyan	50.00	50.00	

The six above toner inks were by design adapted to reproduce the color and intensity of the four filters of each color when mixed or thinned with a known amount of additional uncolored vehicle. This being known, the appropriate amount of the toner ink necessary to tint the base ink to the extent represented by the associated filter was determined for each combination of base color sample and filter. In this regard, the following table was prepared indicating the parts (by weight) of toner ink to be added to 100 parts of the base ink to effectively tint the base ink to the extent indicated by the various filters:

Formulations (Parts Toner Ink per 100 Parts Base Ink)

	Filter A	Filter B	Filter C	Filter D	
1. Red (Group 32)	0.010	0.005	0.0025	.0012	
2. Green (Group 33)	0.006	0.003	0.0015	.0007	65
3. Blue (Group 34)	0.005	0.003	0.0015	.0007	
4. Yellow (Group 35)	0.008	0.004	0.0020	.0010	

5. Magenta (Group 36)	0.008	0.004	0.0020	.0010
6. Cyan (Group 37)	0.002	0.001	0.0006	.0003

5 In the specific test run, a sheet of paper having a portion printed in a somewhat mustard yellow color was selected at random for matching. The sample was placed in the upper half of the viewing area 30 and a base sample of benzine yellow printed on similar paper 10 was positioned immediately adjacent thereto in the lower half of the viewing area. After a certain amount of trial and error, it was determined that the color of the desired sample was closely duplicated when magenta filters A and D were positioned over the base color. Utilizing the above formulation table, 0.009 parts of magenta toner ink were added to 100 parts of base benzine yellow ink. After a thorough mixing, a proof was prepared utilizing the resulting ink. The proof was found to very closely duplicate the original mustard yellow color.

In the drawings and specification, there has been set forth a preferred embodiment of the invention, and although specific terms are employed, they are used in a generic and descriptive sense only and not for purposes of limitation.

What is claimed is:

1. An apparatus for facilitating the formulation of an ink capable of closely duplicating a color having an unknown ink formulation comprising
  - a viewing area for receiving in a juxtaposed relation a sample of the color of unknown ink formulation and a sample of a color of known ink formulation of generally the same color type as the color of unknown ink formulation for simultaneous viewing by an operator,
  - a plurality of transparent filters of differing colors corresponding to colors reproducible by known ink formulations, and
  - means for mounting said filters so as to have selective and independent movement relative to the viewing area to permit viewing of the sample of color of known ink formulation through one or more of the filters and with said filters positioned in spaced relation above said viewing area such that light may be directed onto said viewing area without passing through said filters and the light reflected from said viewing area passes through the selected filters to the operator, whereby a combination of the sample of color of known ink formulation and one or more of the filters may be chosen to closely approximate the color of the sample of unknown ink formulation and the known ink formulations of the selected filters and the known color sample may be mixed to achieve an ink formulation substantially the same as the unknown formulation.
2. An apparatus for duplicating a color of unknown ink formulation to assist in the reproduction thereof comprising
  - a viewing area having a first portion for receiving a color sample of unknown ink formulation and a second portion for receiving a color sample of known ink formulation,
  - eyepiece means for focusing the vision of an observer onto said viewing area,
  - a plurality of transparent filters of differing colors, the color of each of said filters being reproducible by a known ink formulation,

means for mounting said filters in spaced relation above said viewing area and between said viewing area and eyepiece means such that any number of combination thereof may be selectively positioned to overlie said second portion of said viewing area when viewed through said eyepiece means, and means for directing a beam of light onto said viewing area such that an incident light beam is directed onto said viewing area without passing through said filters and a reflected light beam passes through the selected filters and eyepiece means to the observer.

3. The apparatus as defined in claim 2 wherein said means for mounting said filters comprises a plurality of independently pivotable arms, each of said arms carrying a filter and being independently pivotable between a first position wherein said filter overlies said second viewing portion and a second position wherein said filter does not overlie said viewing area.

4. The apparatus as defined in claim 3 further comprising stop members for limiting the pivotable movement of said arms between said first and second positions.

5. The apparatus as defined in claim 4 wherein a number of said arms are pivotable about a common first axis and the remaining arms are pivotable about a common second axis.

6. The apparatus as defined in claim 2 wherein said plurality of filters comprises a number of filters of differing intensities of each color.

7. An apparatus for facilitating the formulation of an ink capable of closely reproducing a desired unknown color comprising

a plurality of samples of differing known colors, a base ink for reproducing the color of each of said color samples,

a plurality of transparent filters of differing colors, a toner ink for reproducing the color of each of said color filters,

a viewing area including a first portion for mounting a sample of the desired unknown color and a second portion for mounting a selected one of said known color samples, and

means for mounting each of the filters in spaced rela-

tion above said viewing area such that light may be directed onto said viewing area without passing through said filters and the light reflected from said viewing area passes through the selected filters and wherein any number or combination of said filters may be selectively positioned to overlie said second viewing area portion to thereby permit the desired unknown color to be approximately reproduced by the known color sample and the superimposed filters, whereby an ink capable of closely reproducing the desired unknown color may be formulated by combining the base ink adapted to reproduce the selected known sample and the toner inks adapted to reproduce the selected color filters.

8. The apparatus as defined in claim 7 further including eyepiece means mounted above said filters for focusing the vision of an observer onto said viewing area.

9. The apparatus as defined in claim 8 further including light means for directing a beam of light onto said viewing area such that the light is reflected from the viewing area and passes through the selected filters and eyepiece means to the observer.

10. A process for formulating an ink capable of reproducing a sample of an unknown color comprising the steps of,

placing a sample of the unknown color and a sample of known color which is reproducible by a known ink in juxtaposition,

selectively positioning one or more filters of differing colors which are each reproducible by a known ink in space relation above the known color sample until the color of the unknown sample is approximately duplicated when the known color sample is viewed through the selected filters, and while directing a beam of light onto the sample of known color and sample of unknown color without passing through said filters and such that the light is reflected from the known color sample through the selected filters and to the observer, and mixing the known inks indicated by the known color sample and the selected filters.
